UNITED STATES PATENT OFFICE.

SILVANUS TINGLEY AND CHARLES W. STETSON, OF BOSTON, MASSACHUSETTS; SAID STETSON ASSIGNOR TO WILLARD W. ANDERSON, OF CAMBRIDGEPORT, MASSACHUSETTS.

CARD-SHUFFLING APPARATUS.

SPECIFICATION forming part of Letters Patent No. 373,953, dated November 29, 1887.

Application filed March 29, 1887. Serial No. 232,849. (No model.)

To all whom it may concern:

Be it known that we, SILVANUS TINGLEY and CHARLES W. STETSON, both of Boston, county of Suffolk, State of Massachusetts, have 5 invented an Improvement in Card-Shuffling Apparatus, of which the following description, in connection with the accompanying drawings, is a specification, like letters on the drawings representing like parts.

10 This invention has for its object to provide an apparatus for thoroughly and quickly shuffling or intermixing playing-cards.

In accordance with our invention we provide a suitable frame or case with two card-holding 15 boxes or chambers at opposite ends of a bed or table upon which the cards fall as they are discharged from the said card-holding boxes or chambers by a suitable feeding mechanism, to be described, the cards coming from opposite directions, falling one upon another and forming a common pile. Each card-receiving box or chamber has a cover provided at its under side with one or more springs, which, when the cover is closed, act upon the uppermost card of the divided pack therein, usually 20 one-half the pack. The bottom plate of each box or chamber is slotted or cut away to permit a feeding mechanism to act upon the lowermost card therein, and the contiguous ends 25 of the boxes or chambers containing the cards are slotted at the level of the bottom plates to enable the cards acted upon by the feeding mechanism to be fed singly out of the boxes or chambers.

30 The feeding mechanism herein shown consists of india-rubber wheels or disks on a short shaft.

Our invention consists, essentially, of a card-shuffling apparatus comprehending two boxes 35 or chambers to receive portions of the cards of the pack to be shuffled and a feeding mechanism to feed the cards out of the said chamber and deposit them in a pile between the said boxes, as will be described.

40 Figure 1 is a longitudinal section of a card-shuffling apparatus embodying our invention, and Fig. 2 is a top or plan of our improved apparatus with one of the covers raised.

Our improved card-shuffling apparatus is

composed, essentially, of a case or frame, a a' 50 a^2 , cut away centrally to support a bed or table, a^3 , and having at each end of the said table a card-receiving box or chamber for the reception of the cards, B , to be shuffled, about one-half of the pack being placed in each box. 55 The bottoms b of these boxes or receptacles are provided with slots or openings b^2 , through which pass the disks or wheels b^3 of the feeding mechanism, the said disks or wheels, covered, preferably, with india-rubber, being connected 60 to arbors b^3 , having suitable fixed bearings. The arbors b^3 are provided each with a toothed pinion, b^6 , engaged and rotated by a toothed gear, d , having bevel-teeth, which are engaged by bevel-gears d^2 , fast on the shaft d^3 , the 65 shaft being provided with a crank or handle, d^4 . The contiguous ends of the boxes or chambers next the ends of the bed or table are slotted opposite the ends of the bottom plates b , to enable the feeding mechanism set in motion 70 by turning the crank d^4 to act upon the lowermost cards of the partial packs B and feed them in succession out of the boxes or chambers upon the bed or table a^3 , the said cards coming upon the said bed or table from opposite 75 directions and one after another in a common pile, ready to be taken up by the dealer.

We do not desire to limit our invention to the exact form of feeding mechanism herein shown, nor to the exact devices employed to 80 rotate the arbors b^3 , for instead of the devices shown we may use any other well-known or suitable means or devices to eject the cards one at a time from two or more boxes or chambers into a common pile.

85 The card-receiving chambers or boxes a a' are respectively provided with covers e^4 e^5 , to the under side of which are secured one end of suitable springs, e^1 , the other or free end of the said springs bearing upon the uppermost 90 cards of the partial packs when the covers are closed.

In the operation of our improved apparatus the cards are divided and part placed in one and part in the other chamber or box. The 95 covers are then closed and the operator turns the crank-handle d^4 in the direction of arrow 20, to cause the disks b^5 b^6 to feed the lower-

most cards in succession from the chambers a^6 a^7 , the said cards falling one upon the other upon the base or table a^3 , the cards being in this manner thoroughly shuffled.

5 We claim—

1. An apparatus for shuffling cards, it consisting, essentially, of two boxes or chambers to receive portions of the cards of the pack to be shuffled and a feeding mechanism to feed 10 the cards out of the said chambers and deposit them in a pile between said boxes, substantially as described.
2. In an apparatus for shuffling cards, two chambers or boxes to contain the cards, and a 15 feeding device to act upon the lowermost card of the partial pack in each chamber, combined with means, substantially as described, to rotate the feeding devices to feed the cards out of their chambers, as and for the purpose 20 specified.

3. In an apparatus for shuffling cards, two chambers or boxes to contain the cards, a feeding device to act upon the lowermost card of the partial pack in each chamber, and means to act upon the uppermost card to keep the lowermost card in contact with the feeding device, combined with means, substantially as described, to rotate the feeding devices to feed the cards out of their chambers, substantially as specified. 25

In testimony whereof we have signed our names to this specification in the presence of two subscribing witnesses. 30

SILVANUS TINGLEY.
CHARLES W. STETSON.
